US00D516922S

(12) **United States Design Patent** (10) Patent No.: **US D516,922 S**
Stockwell et al. (45) Date of Patent: **** Mar. 14, 2006**

(54) **BOTTLE PORTION**

(75) Inventors: **Machelle D. Stockwell**, Bradenton, FL (US); **Stuart Leslie**, Larchmont, NY (US); **Charles A. Curtiss**, Norwalk, CT (US); **Tomohito Asano**, New York, NY (US); **David Deemer**, Adrian, MI (US); **Hassan Mourad**, Canton, MI (US)

(73) Assignee: **Stokely-Van Camp, Inc.**, Chicago, IL (US)

(**) Term: **14 Years**

(21) Appl. No.: **29/222,031**

(22) Filed: **Jan. 25, 2005**

(57) **CLAIM**

The ornamental design for a bottle portion, as shown and described.

DESCRIPTION

FIG. 1 is a perspective view of a bottle portion showing the new design;

FIG. 2 is an elevational view thereof, the opposite elevational view being identical;

FIG. 3 is another elevational view thereof, representing a half rotation of the bottle portion about its vertical axis from the elevational view depicted in FIG. 2, the opposite elevational view being identical;

FIG. 4 is a top plan view thereof;

FIG. 5 is a bottom plan view thereof;

FIG. 6 is a perspective view of a first embodiment of a bottle portion showing the new design;

FIG. 7 is an elevational view thereof, the opposite elevational view being identical;

FIG. 8 is another elevational view thereof, representing a half rotation of the bottle portion about its vertical axis from the elevational view depicted in FIG. 7, the opposite elevational view being identical;

FIG. 9 is a top plan view thereof; and,

FIG. 10 is a bottom plan view thereof.

The broken line environmental showing is for illustrative purposes only and does not form a part of the claimed design.
